FUR CARROTTING MACHINE

Joseph F. Ellis, Danbury, Conn.

Application February 2, 1949, Serial No. 74,102

4 Claims. (Cl. 69—28)

1

The present invention relates to an improved fur carroting machine.

Numerous attempts have been made in the past to provide machines for carroting skins to replace the usual hand operation. The principle involved in applying a carroting solution to the fur of a skin is substantially the same in both a hand operation and a machine operation, namely, the use of a brush for applying a carroting solution, such for example as nitrate of mercury, Farian Carrot or any other non-mercuric acid and working it into the fur during the brushing operation.

The present machine comprises a rotary brush provided with novel means for distributing over its surface the proper quantity of carroting solution and adapted to impregnate therewith the fur of the skin which passes beneath the brush, the skin being fed beneath the rotating brush by suitable conveying mechanism.

A further feature of the present invention is the provision of a novel conveying and supporting apparatus for the fur skins consisting of a series of stainless steel slats suitably spaced to receive the prongs of rollers positioned below the slats whereby rotation of the rollers will move the skins along the slats in contact with rotating brushes above the slats.

A still further feature of the present invention is the provision of a compact, simplified apparatus for uniformly and more thoroughly applying the carroting solution to the fur being treated and employing a novel arrangement for preventing waste of the carroting solution.

Other features and advantages of the present invention will be readily apparent from the following detailed description of a preferred embodiment of the invention shown in the accompanying drawings wherein:

Figure 1 is a side elevation of the left half of the present improved apparatus.

Figure 1a is a side elevation of the right half of the apparatus.

Figure 2 is a front elevation of the apparatus.

Figure 3 is a diagrammatic view of the passage of the skins through the apparatus.

Figure 4 is a perspective view of a portion of the apparatus showing the manner of supplying the acid.

Figure 5 is a sectional perspective view of the picker conveying mechanism.

Referring to the drawings in detail, numeral 10 indicates the main frame structure in the form of a table supporting the movable parts of the ap-

2

paratus. The frame structure is suitably braced to form a rigid support and is provided with brackets on either side serving as supports for the feeding mechanism.

Referring to Figure 1, the feeding means for the fur pelt comprises a conveyor apron or endless belt 11, supported on a pair of rollers 12 and 13. The roller 12 is suitably supported for rotation by the bracket 14 extending from the frame member 10. The roller 13 lies within the frame member and is suitably supported by means of a bracket member 15.

A similar conveyor arrangement is provided at the exit end of the apparatus and is shown more clearly in Figure 1a. It consists of an endless belt 16, carried by rollers 17, mounted on a supporting frame 18 which latter extends from the frame 10 in a position opposed to the frame member 14.

Supported above the frame 10 and forming the table top for the frame are a plurality of flat slats 19. These slats are preferably formed of stainless steel, or could be of any suitable acid resistant metal. These slats are longitudinally spaced across the width of the frame and are held in such position by cross bars 20 to which the slats are joined by welding or the like. As seen in Figures 3 and 5, the forward end of the slats 19 are curved downwardly for a purpose to be described.

The means for conveying the pelts through the main part of the apparatus comprises a plurality of rollers known as pickers indicated by the numeral 21. These pickers carry a series of pins or prongs 22 suitably spaced along the length of the roller to extend into the spaces between the metal slats 19. The pins 22 are also spaced about the periphery of the roller as clearly seen in Figures 3 and 5. The rollers 21 are rotatively mounted on the frame member 10 immediately below the slats 19 and the prongs or pins 22 are of sufficient length to penetrate the skin of the pelt lying on the slats 19. This provides for feeding and proper positioning of the pelts during the carroting operation.

A plurality of conveyor rollers 23 are positioned at various points immediately above the conveyor belts 11 and 16 and slats 19 to feed the pelt 24 through the apparatus. The carroting solution 25 is applied to the fur of the pelt by a large brush 26 located adjacent the entrance side of the apparatus. The acid or carroting solution is supplied to brush 26 by the supply brush 27 which in turn is supplied by the perforated supply pipe 28. The pipe 28 is supplied with the acid by a pump 29 interposed in the pipe line 30 running between the supply pipe 28 and the acid

supply tank 31. A hand control valve 32 may be provided to shut off the supply of acid when desired or to regulate the amount of acid supplied to the supply pipe 28. An acid tank 33 is mounted adjacent the supply brush 27 with a portion thereof cut away at 34 to underlie the supply brush to receive any excess acid dripping off the brush. A return pipe 35 connected at the underside of tank 33 returns the excess acid to the supply tank 31 where the acid may be recirculated to the supply brush 27.

Mounted rearwardly of the large brush 26 are a pair of spaced brushes 36 and 37 which serve to rub off any excess acid on the skins and slick the hairs on the skin down. As seen in Figure 3, the conveyor rollers 23 are interposed between the various brushes to assure proper conveying of the pelt through the apparatus.

The various brushes and conveyors may be driven by any suitable driving means. The driving means may consist of an electric motor and reduction box generally indicated by numeral 38 suspended from the bracket 18 by supporting members 39. The motor is connected to the various brushes and rollers through suitable gearing and sprocket chains. The picker rolls are so arranged as to rotate a little slower than the brushes thereby enabling the brushes to more thoroughly rub the fur, remove the excess acid and slick the hairs down. Any suitable gearing for accomplishing this result may be used.

The operation is as follows:

The skins are placed on the conveyor apron 11 with the fur extending upwardly, said apron moving the skins to the first of the rolls 23 which brings the skins into contact with the stainless steel strips 19, the brush 26 and the first of the picker rolls 21. The picker pins 22 penetrate the skins and form an effective means for feeding the skin or pelt at a uniform speed through the apparatus. The pins also serve to hold the skins against shifting during the brushing operation for both applying the carroting solution and working the same into the fur of the skin. The carroting solution which is stored in the tank 31 is pumped to the perforated supply pipe 28 through the pipe 30 by means of pump 29 and is there evenly distributed to the supply brush 27. The supply brush 27 rotates in a direction opposite to the rotation of the brush 26 and as it contacts said brush, it deposits the solution on said brush which in turn applies the solution to the fur skins as the brush contacts the skins during the passage of the skins through the apparatus. Any excess solution dripping off the supply brush 27 drops into the tank 33 and is returned to the supply tank through pipe 35. This construction insures an even supply of carroting solution to the brush 26 and in turn to the fur skins. As the skins advance after the carroting solution is applied to the fur, they come into contact with the slicking brushes 36 and 37 which work the solution into the fur and rub off any excess solution. At the outlet end of the apparatus, the skins are carried to the conveyor 16 where they may be removed or directed to a suitable receiver.

It will be noted that the location of the slats between the brushes and the picker rolls will insure a proper passage of the skins through the apparatus. Since the picker rollers rotate about a fixed axis, the slats form a simple way of stripping the skins from the last picker roll as the skins are moved onto the conveyor belt 16.

Owing to the construction and arrangement

of the various parts of the machine and to the mode of operation, the carroting operation is both thorough and rapid.

It will be understood that various changes in details of construction can be made without departing from the spirit of the invention, the scope of which is commensurate with the appended claims.

Having thus described the invention, what is claimed is:

1. In a fur carroting machine, a plurality of spaced slats for supporting a pelt thereon, a plurality of rollers rotatably mounted below said slats and having spaced pins mounted thereon adapted to extend into the space between adjacent slats to penetrate the pelt and propel it along the slats, a brush rotatably mounted above the slats to apply a carroting solution to the fur pelt, a second brush located above said first brush for supplying carroting solution to said first brush, and a perforated pipe for supplying carroting solution to said second brush.

2. In a fur carroting machine, a conveying mechanism for propelling fur pelts through the machine, a brush located above the conveying mechanism for applying a carroting solution to the pelts, a second brush for supplying the carroting solution to said first brush, a perforated pipe for supplying the carroting solution to the second brush, a supply tank for the carroting solution and a second tank for receiving any excess solution from the second brush and returning same to said supply tank.

3. In a fur carroting machine, a conveying mechanism for propelling fur pelts through the machine, a brush located above the conveying mechanism for applying a carroting solution to the pelts, a second brush for supplying the carroting solution to said first brush, a perforated pipe for supplying the carroting solution to the second brush, a supply tank for the carroting solution, a second tank for receiving any excess solution from the second brush and returning same to said supply tank, and means for regulating the amount of carroting solution supplied to said perforated pipe.

4. In a fur carroting machine, a plurality of spaced slats for supporting a fur pelt thereon, a plurality of rollers rotatably mounted below said slats and having spaced pins mounted thereon and extending between adjacent slats to penetrate the pelt and propel it along the slats, a first brush rotatably mounted above the slats to apply a carroting solution to the fur pelt, additional brushes mounted above the slats to work said carroting solution into the fur pelts, and rollers above said slats for pressing the fur pelts against said slats.
